Patented June 29, 1920.

FIG. 1

FIG. 2

Thomas W. Arter Inventor

By *Geo. P. Kimmel.*

Attorney

UNITED STATES PATENT OFFICE.

THOMAS W. ARTER, OF BELLAIRE, OHIO.

CUSHION-HEEL.

1,345,114.

Specification of Letters Patent. Patented June 29, 1920.

Application filed June 3, 1919. Serial No. 301,429.

To all whom it may concern:

Be it known that I, THOMAS W. ARTER, a citizen of the United States, residing at Bellaire, in the county of Belmont and State 5 of Ohio, have invented certain new and useful Improvements in Cushion-Heels, of which the following is a specification.

The present invention comprehends generally improvements in that class of inventions 10 known as boots and shoes and more particularly has reference to a cushion heel.

The invention has for its principal aim and object to provide a device of the above mentioned character designed in the form of 15 an attachment for engagement with the heel of a shoe to yieldingly support the heel of the wearer of the shoe and as a result increase the comfort thereof.

More particularly, the present invention 20 contemplates the provision of a device of the above mentioned character composed of an attaching and supporting frame in which is fitted the resilient member also designed to be accommodated within a portion of the 25 heel of the shoe at the time the frame is anchored in position, the latter incidentally being designed to fasten the heel portion of the upper of the shoe to the heel portion of the sole thereof.

It is a more specific object of this invention 30 to provide a device of the above mentioned character wherein the attaching and supporting frame is of novel construction capable of being stamped from a piece of 35 metal and subsequently bent to assume the desired form.

Among the other aims and objects of this invention may be recited the provision of a device of the above mentioned character 40 wherein the number of parts are comparatively few, the construction simple, the cost of production low and the efficiency high.

Other objects, as well as the nature, characteristic features and scope of this invention 45 will be more readily apparent from the following description taken in connection with the accompanying drawings and pointed out in the claims, forming a part of this specification.

The invention is clearly illustrated in the accompanying drawings, in which:

Figure 1 is a longitudinal sectional view 50 through the heel and heel portion of the upper of a shoe showing the cushioning member in position,

Fig. 2 is a top plan view of the supporting frame *per se*, and

Fig. 3 is a side elevation of the said frame. Similar characters of reference are employed in all of the above described views, 60 to indicate corresponding parts.

Referring now, more particularly, to the accompanying drawings, there is provided a shoe generally designated by the numeral, consisting of a sole 2 and an upper 3, while 65 to the under surface of the heel portion of the sole is attached the heel 4, the body of which is composed of a plurality of superposed sections or layers 5 of leather. The heel portion of the sole and the body of the 70 heel are formed with a curved bottomed recess 6 in which is fitted the cushioning member designated in its entirety by the numeral 7.

In reducing the present invention to practice, the same may be said to be in the form of an attachment and consists of a frame 8 in the shape of a heel, preferably stamped from sheet metal and formed at suitable intervals along its outer edges with attaching or anchoring spurs 9, preferably positioned to depend therefrom so as to engage the in-turned portion 10 of the upper of the shoe for fastening the same to the sole when the spurs themselves are anchored in the heel portion of the sole and the body of the heel as indicated in Fig. 1. The inner edges of 75 the frame are split as at 11 at uniformly spaced intervals while the portions between the slits constitute supporting and engaging 80 flanges 12 formed by the alternately inclining of said portions upwardly and downwardly with respect to the frame, and in effect forming a groove in which is fitted the outer edges of the resilient body 13 preferably of rubber. This body conforms to the 85 shape of the frame and preferably is of an oval shape configuration in cross section so as to lie in engagement with the recess 6 and also above the upper surface of the heel portion of the sole, the arrangement being indicated in Fig. 1.

To increase the comfort of the wearer of the shoe and at the same time prevent the upper flanges 12 from injuring the heel of 105 the foot, a lining 14 is arranged within the shoe and lies over the sole and the cushioning extension for the heel as indicated.

It is believed that in view of the foregoing description that a further detailed descrip- 110

tion of the operation of the invention is entirely unnecessary. Likewise, it is believed that the advantages of the invention will be readily apparent.

5 Still further embodiments of the invention than those herein especially defined may be resorted to as conditions or preference may dictate, as may be in keeping with in hereto appended claims.

10 Having thus fully described the invention, what is claimed as new and desired to be secured by Letters Patent, is:

1. In a device of the character described, in combination with the heel of a shoe having a recess in the upper surface thereof, an attaching frame having its inner edges alining with the upper edge of the recess and also split at uniformly spaced intervals, the portions lying between the slits being alternately bent upwardly and downwardly to

provide supporting and engaging flanges and also forming a groove, anchoring spurs depending from the frame and anchored in the heel and a resilient element having its reduced outer edges seated in the groove 25 with the lower surface engaging the recess and the upper surface positioned in a plane above the plane of the frame.

2. A heel cushion for shoes comprising an attaching frame having its inner edge slit at intervals and the portions lying intermediate the slits being bent alternately upwardly and downwardly to provide confining flanges, and a cushioning element having a tapered edge removably confined between said flanges.

In testimony whereof I affix my signature hereto.

THOMAS W. ARTER.
